US00D747735S

(12) **United States Design Patent**
Jung et al.

(10) **Patent No.:** US D747,735 S
(45) **Date of Patent:** ** Jan. 19, 2016

(54) **DISPLAY SCREEN OR PORTION THEREOF WITH ICON**

(71) Applicant: **Samsung Electronics Co., Ltd.**, Suwon-si (KR)

(72) Inventors: **Yong-Chae Jung**, Seoul (KR); **Su-Hyun Na**, Seoul (KR)

(73) Assignee: **Samsung Electronics Co., Ltd.**, Suwon-si (KR)

(**) Term: **14 Years**

(21) Appl. No.: **29/458,123**

(22) Filed: **Jun. 17, 2013**

(30) **Foreign Application Priority Data**

Feb. 23, 2013 (KR) 30-2013-0009606
(51) **LOC (10) Cl.** **14-14**
(52) **U.S. Cl.**
USPC **D14/489**
(58) **Field of Classification Search**
USPC D14/485-495

(57) **CLAIM**

The ornamental design for a display screen or portion thereof with icon, as shown and described.

DESCRIPTION

FIG. 1 is a front view of a display screen or portion thereof with icon, showing our new design; and,

FIG. 2 is a front view of a second embodiment thereof. The broken lines represent a boundary and form no part of the claimed design.

1 Claim, 2 Drawing Sheets

FIG. 1

FIG. 2
